UNITED STATES PATENT OFFICE.

CARL M. YODER, OF CLEVELAND, OHIO.

ROLLING OR BENDING MACHINE.

1,376,497.

Specification of Letters Patent.

Patented May 3, 1921.

Application filed December 11, 1916. Serial No. 136,351.

To all whom it may concern:

Be it known that I, CARL M. YODER, a citizen of the United States, residing at Cleveland, in the county of Cuyahoga and State of Ohio, have invented certain new and useful Improvements in and Relating to Rolling or Bending Machines, of which the following is a specification.

This invention relates to a machine for bending or rolling metal, particularly of the type adapted to bend or roll metal sheets or plates into automobile fenders, barrel bodies and other articles.

One object of the invention is to provide an improved machine of this character comprising few parts and capable of rapid operation.

Another object of the invention is to provide improved means for rolling or bending a section of metal into curvilinear shape.

Another object of the invention is to provide means for rolling or bending a section of metal both longitudinally and transversely.

Another object of the invention is to provide means for rolling or bending a section of metal both longitudinally and transversely to any shape or degree of curvature.

With these and other objects in view the invention consists of the parts or combination or combinations of parts hereinafter set forth.

For the purpose of illustration I have, in the accompanying drawings, shown and herein described one form of apparatus embodying my invention.

Figure 1 is a front elevation of a rolling or bending machine embodying my invention.

Fig. 2 is a top plan view thereof.

Fig. 3 is a fragmentary elevation looking at the rear side of the machine.

Fig. 4 is an end elevation of the machine.

Figs. 5, 6 and 7 are fragmentary sectional views.

Fig. 8 is a section (enlarged) on the line 8-8 of Fig. 9.

Fig. 9 is a fragmentary plan view, the roller 5^b being omitted.

Fig. 10 is a longitudinal sectional view of the bending shoe.

Figs. 11 and 12 are fragmentary sectional views illustrating the operation of the bending devices.

Figs. 13 and 14 are perspective views of a

section of metal in different stages of formation.

Figs. 15 and 16 illustrate modified forms of bending devices.

Fig. 17 is a section on the line 17-17 of Fig. 8.

In the drawings, 1 indicates a frame or support preferably comprising a bed 1^a mounted on legs 1^b. 1^c indicates a pair of standards fixed in any suitable manner to the bed 1^a, preferably by bolts 1^c. The bolts 1^c permit the standards 1^c to be removed at any time whereby certain elements of the machine can be removed and elements of a different size or shape substituted. At 1^d the standards 1^a are cut away or provided with guides to receive pairs of bearing blocks or members 2, 2'. This form of construction permits the upper shaft to be raised and lowered for purposes to be later set forth.

3, 3', indicate a pair of shafts supported at their opposite ends by the bearing blocks 2, 2', respectively. The purpose of the shafts 3, 3', will be later described.

4 indicates as an entirety the mechanism, which, for purposes of illustration, I prefer to use for driving the shafts 3, 3'. Of this mechanism, 4^a indicates a shaft supported at its opposite ends in bearings 4^a, 4^a', supported on the machine bed 1^a. 4^b, 4^b', indicate a pair of driving elements, preferably pulleys, loosely mounted on the shaft 4^a and adapted to be driven in opposite directions by suitable belts (not shown), one of which may be crossed. 4^c indicates clutch devices

preferably interposed between the pulleys 4^b, 4^b', and adapted to be locked to either pulley in a well known manner, whereby the shaft 4^a may be driven in one direction or the other, as desired. 4^d indicates a gear fixed to the shaft 4^a and meshing with a gear 4^e fixed to the adjacent end of the shaft 3 to drive the latter. 4^f, 4^f' indicate two gears, preferably of the same size, fixed to the shafts 3, 3', respectively, and meshing with each other, whereby the shaft 3' is driven in the opposite direction to, but at the same speed as, the shaft 3. The clutch devices 4^c are preferably operated by a lever 4^g, fulcrumed on the bed 1^a in any suitable manner.

At one end the lever 4^g is connected through a link 4^h to a hand lever 4ⁱ by which the operative can quickly and effectively control the operation of the

machine. It will be understood that when the clutch element 4^c is in mid-position the clutch devices 4^c are not connected to either pulley 4^b. Two operating connections 4^g, 4^h, and 4ⁱ, disposed on opposite sides of the machine, are preferably provided so that the machine can be controlled from each side.

5 indicates as an entirety the devices 10 which bend or roll a section of metal on transverse lines into circular or curvilinear shape and also bend or roll it on longitudinal lines into the desired cross sectional shape.

15 The bending devices 5 preferably comprise a pair of co-operating rollers 5^a, 5^b, fixed to the shafts 3, 3', respectively, and a shoe 5^c which co-acts with the rollers 5^a, 5^b. I prefer to so correlate the rollers 5^a, 5^b, and 20 shoe 5^c, that the section of metal will be bent or curved upwardly; in that event the shoe 5^c is positioned at any predetermined point relative to the plane of that portion of the metal which at any time is passing between the rollers 5^a, 5^b, and preferably at an angle 25 thereto, according to the curvature to be imparted to the section of metal.

The bending devices 5^a, 5^b and 5^c may be 30 of any desired shape. In Figs. 1, 2, 3, 8, 9, 10, 11 and 12 I have illustrated bending devices which will bend or roll the metal into convexed-concavo shape; in Figs. 15 and 16 the bending devices 5^a, 5^b, are shaped at 5^{a'}, 5^{b'}, to provide a flat portion at either side 35 of the metal section; in Fig. 16, the bending devices are also shaped at 5^{a''}, 5^{b''}, to provide the metal section with beads. It will be understood that where bending elements of the shape illustrated in Figs. 15 and 16 40 are used, a shoe 5^c, having a similarly shaped edge, is preferably provided.

The shoe 5^c is preferably swingable about the axis of the bending device 5^a, as will be later described, so that the metal sections 45 can be bent on transverse lines to any desired degree of curvature and the operations of bending and rebending metal sections can be rapidly carried on. The roller 5^a is preferably provided at its opposite 50 ends with collars 5^{ax} which serve as guides for the metal section as it passes between the rollers 5^a, 5^b. The roller 5^a may be removably fixed to the shaft 3 in any suitable manner; I prefer to provide the shaft with 55 a key or spline 3^a which fits into an axially extending recess formed in the walls of the opening through the roller 5^a. 5^{bx} indicates collars arranged on the shaft 3 at either side of the roller 5^a and adapted to be secured to 60 the shaft, preferably by set screws 3^b, to prevent movement of the roller endwise thereof. The key 3^a serves to secure the roller 5^a to the shaft so as to drive the roller therewith, but permits the roller to be removed and a 65 roller of a different size or shape substituted

upon the disassembly of one of the collars 5^{bx} and adjacent standard 1^c. The roller 5^b is preferably fixed to the shaft 3' by a key or spline 3^{a'} which fits a recess formed in the inner wall of the roller 5^b. The key or 70 spline 3^{a'} serves to connect the roller 5^b to the shaft 3' so as to be driven thereby, but permits the roller to be moved endwise for removal purposes. As shown in the drawings, the roller 5^b is disposed between the 75 collars 5^{ax} and is thereby prevented from moving endwise; as a result, no additional devices are required to maintain the roller 5^b in alignment and co-operative relationship with roller 5^a.

The shoe 5^c is shaped to substantially conform to the surface of the roller 5^a and is positioned rearward of the roller so as to engage the metal section immediately after it passes between the rollers 5^a, 5^b. The normal position of the shoe 5^c is best illustrated in Figs. 3, 4, 5 and 17 and when it is in that position the metal may be passed through between the rollers without being acted upon by the shoe; but by moving the 80 shoe upwardly it will be disposed in the path of the metal and cause the same to be bent or rolled, as shown in Figs. 11 and 12. By mounting the shoe to swing on the axis of the roller 5^a it may be disposed at different angles relative to the plane of the metal section between the rollers 5^a, 5^b, according to the desired curvature to be imparted to the metal section and at the same time maintained at the same distance from the 85 surface of the roller 5^a.

6 indicates a frame for adjustably or swingably supporting the shoe 5^c. The frame preferably comprises a pair of ring members 6^a, 6^a, loosely mounted on the shaft 105 3, and a member 6^b which rigidly connects the ring members 6^a together. Each ring 6^a is provided with an arm 6^{a'} to which the adjacent end of the connecting member 6^b is secured and also provided with a plurality 110 of gear teeth 6^c for a purpose to be later described. The shoe 5^c is fixed in any desired manner to the connecting member 6^b, preferably by bolts 6^d, which permit the ready removal of the shoe. The member 6^b 115 may be concaved throughout its central portion to conform to the shape of the shoe 5^c. The opposite ends of the supporting member 6^b may be connected to the arms 6^{a'} of the rings 6^a by devices, indicated as an entire 120 at 7, which provide for the adjustment of the member 6^b both vertically and horizontally and through it the adjustment of the shoe 5^c, so that the latter may be adapted for different thicknesses of metal. The devices 7 preferably comprise pairs of 125 screws 7^a which have screw-threaded engagement with openings formed in either end of the connecting member 6^b and adapted to engage the adjacent arm 6^{a'}, and a 130

bolt 7^b extending through a slotted opening 7^{b'}, formed in either end of the connecting member 6^b and having screw-threaded engagement with an opening 7^c formed in the adjacent arm 6^a. To adjust the connecting member 6^b, the bolt 7^b is loosened and thereafter the screws 7^a are turned in one direction and the other to elevate or lower the connecting member 6^b; then the bolt 7^b is 5 screwed down tightly, thus locking the connecting member 6^b to the adjacent arm 6^a. The slot 7^{b'} being elongated, it permits the connecting member 6^b to be moved horizontally or toward and from the rollers 5^a, 5^b, 10 so that the shoe 5^c can be adjusted toward and from the adjacent roller, as well as vertically. By operating the screws 7^a and bolt 7^b, the member 6^b may be adjusted vertically—at right angles to the tangential plane 15 in which the shoe is supported—and also inclined relative to such plane. 8 indicate as an entirety means for operating or swinging the shoe 5^c about the axis of the roller 5^a. These means preferably 20 comprise a rock-shaft 8^a supported at its opposite ends in suitable bearings provided in the standards 1^c, 1^c, a pair of gears 8^b fixed to the shaft 8^a and meshing with the teeth 6^c provided on the ring members 6^a, and a 25 handle 8^c suitably connected to the rock-shaft 8^a for operating it. The handle 8^c may consist of a pair of rods 8^c connected to and extending radially from the gears 8^b and provided at their outer ends with a 30 cross bar 8^d adapted to be grasped by an operative. 8^e indicate collars fixed in any suitable way to the shaft 8^a, near its opposite ends, and by engagement with the inner walls of the standards 1^c, prevent end- 35 wise movement of the shaft. 40 9 indicates a spring connected at one end to some stationary part of the machine and at its opposite end to one of the rods 8^c. The spring 9 operates to pull the operating means 8 upwardly and through it normally to maintain the bending shoe 5^c in normal position, as shown in full lines in Fig. 5. 45 By this construction the shoe is normally positioned at a point below the section of metal as it is fed through between the rollers 5^a, 5^b, and thereafter may be moved upwardly for engagement with the under side of the metal section for the purpose of bending it to the desired degree of curvature. 50 55 10 indicates a pair of guides carried by the frame 6 rearward of and in line with the collars 5^a provided on the adjacent roller 5^a. The guides 10 are arranged to coöperate with the collars 5^a so as to guide the metal rearwardly while being bent by the shoe 5^c. The guides 10 are preferably secured in position by bolts 6^d. 60 65 11 indicates a shoe which is arranged in front of the rollers 5^a, 5^b, and adapted to support and guide the section of metal

therebetween. The front edge of the shoe 11 is preferably shaped so as to fit close against the circumferential surface of the roller 5^a.

11^a, 11^a, indicate a pair of guide members 70 which coöperate with the shoe 11 to guide the section of metal between the rollers 5^a, 5^b. The guide members 11^a are suitably supported by devices, indicated as an entirety at 12. The guides 11^a are preferably provided 75 with inwardly extending flanges 11^b to which the opposite ends of the shoe 11 are secured in any well known manner. The supporting means 12 preferably comprise a cross bar 12^a having elongated slots 12^b 80 formed in its opposite ends adapted to fit over bolts 12^c which have screw-threaded engagement with an adjacent part of the frame 1. By loosening the bolts 12^c the cross bar 12^a can be raised or lowered as desired. 12^d indicates a pair of plates, each 85 preferably integrally formed with the adjacent guide 11^a. The plates 12^d are preferably formed at opposite sides with elongated slots or recesses 12^e through which the 90 bolts 13 extend. The bolts extend into screw-threaded openings 13^a formed in the cross bar 12^a and serve to secure the plates 12^d thereto. By loosening the bolts 13 and moving the plates 12^d horizontally the 95 guides 11^a can be adjusted toward and from each other. Where considerable adjustment is required, the bolts 13 can be removed from one pair of openings 13^a and inserted in another pair to space the guides 100 11^a at the proper distance relative to each other.

14 indicates as an entirety devices for raising and lowering the shaft 3', whereby the roller 5^b can be elevated should it become necessary to separate the rollers to remove a section of metal therefrom. These devices preferably comprise a pair of arms 14^a pivotally mounted at their lower ends upon the shaft 3. At their upper ends the 110 arms 14^a are provided with openings 14^b to receive eccentrics 14^c. Each eccentric 14^c is provided with a bearing through which the shaft 3' extends. By rotating the eccentric the shaft 3' will be raised and lowered, as indicated by dotted lines in Fig. 6. As the arms 14^a are pivotally mounted upon the shaft 3 the operation of the eccentric will cause the shaft 3' to move upwardly, but due to the engagement of the bearing 115 blocks 2' with the guides 1^d, such operation will cause the arms 14^a to swing laterally about the shaft 3.

15 indicates the devices for operating the eccentrics 14^c. These devices preferably 125 comprise handles 15^a having ring members 15^b which surround the eccentrics 14^c. At one side the walls of each ring member 15^b are split, as shown at 15^c, to permit the ring 15^b to be positioned over the adjacent eccen- 130

tric 14^c. 15^a indicates a bolt which extends through an opening formed in a lug fixed to the wall of the ring member at one side of the split and having screw-threaded engagement at its inner end with an opening formed in a lug fixed to the wall of the ring member on the other side of the split. The bolt 15^a serves to draw the split wall together and thereby secure the ring member to the eccentric. The handles 15^a are preferably connected together by a cross bar 15^e in order that both eccentrics will be operated simultaneously. 16 indicates a locking member which serves to lock the handles in normal position with the roller 5^b in co-operative relationship to the roller 5^a. The locking member preferably comprises a swingable latch having a suitable notch 16^a which is adapted to engage a shoulder 17 preferably extending laterally from the adjacent standard 1^c. I preferably provide two locking members 16 and pivotally connect them to the opposite ends of the cross bar 15^e.

25 In operating the machine, the section of metal is positioned between the guides 11^a and upon the shoe 11. I preferably use metal sections which are flanged along their opposite ends and of a width slightly greater than the distance between the guides 11^a. As a result, the front end of each metal section is first forced down between the guides so as to permit it to extend between and be fed to the bending elements 5^a, 5^d. After 30 a metal section is positioned for feeding, the lever 4ⁱ is operated to throw the clutch into engagement with one of the pulleys 4^b. This operation will rotate the rollers 5^a, 5^b, which in turn will draw or feed the metal section forwardly; at the same time, the bending element 5^c is swung upwardly for co-action with the bending elements 5^a, 5^b, as shown in Fig. 11; as the metal section feeds forwardly the elements 5^a, 5^b, operate 35 to bend it on longitudinal lines and the element 5^c operates to bend the section on transverse lines, into the shape shown in Fig. 13, these operations taking place substantially simultaneously. When it is desired to impart to the section of metal a greater curvature, as shown for instance in Fig. 14, the metal section is re-fed between the bending elements 5^a, 5^b, 5^c, the bending element 5^c being moved upwardly a slight 40 distance (see Fig. 12) each time the metal section is fed through the machine. This operation is repeated until the metal section is curved to the desired extent.

45 By providing the machine with two oppositely driven pulleys 4^b and a clutch for engagement with either one, I am enabled to rotate the rollers 5^a, 5^b, in either direction. Accordingly, in the use of my machine it is not necessary to feed each section 50 of metal forwardly, remove the section and

then start it through the machine again; but by shifting the clutch 4^c and rotating the rollers in opposite directions, the metal section can be moved rearwardly until its front end is between or in position to be fed between the rollers 5^a, 5^b. By operating the machine in this manner the metal section may be rapidly fed forwardly and backwardly from end to end between the rollers until it is bent to the desired shape. In so operating the machine, it will be understood that during the rearward feeding of the metal section the shoe 5^c is preferably moved into an inoperative position, but upon the reversal of the rollers, the shoe is quickly readjusted to act on the metal section as it is fed forwardly.

55 In operating the machine the operatives soon become trained to curve the metal sections to substantially the same shape, but where accurate duplication of sections is essential, a stop 17ⁱ may be provided in the path of the handle 8^c to limit the swinging movement thereof. The stop 17ⁱ preferably comprises a bolt having screw-threaded engagement with the walls of an opening formed in a bracket 17^a fixed to the bed 1^a. The bolt may be turned so as to adjust the height of its head and thereby stop the handle 8^c at any desired point. The bolt 17 may 60 be locked in its adjusted position by a nut 17^c.

65 To those skilled in the art of making apparatus of the class described, many alterations in construction and widely differing 70 embodiments and applications of my invention will suggest themselves, without departing from the spirit and scope thereof. My disclosures and the description herein are purely illustrative, and are not intended 75 to be in any sense limiting.

75 What I claim is:

1. In a machine of the class described, the combination of a pair of rollers, a pair of shoes arranged at opposite sides of said rollers, each disposed in a plane extending tangentially to the periphery of one of said rollers and coöperable with said rollers to bend a section of metal on transverse lines, means for fixably supporting one of said shoes, and means for supporting the other shoe to swing about the axis of one of said rollers, said swingable shoe being shaped transversely substantially similar to the shape of said rollers.

80 2. In a machine of the class described, the combination of a pair of rollers, a pair of shoes arranged at opposite sides of said rollers, each disposed in a plane extending tangentially to the periphery of one of said rollers and coöperable with said rollers to bend a section of metal on transverse lines, means for fixably supporting one of said shoes, means for supporting the other shoe to swing about the axis of one of said rollers,

- ers, said swingable shoe being shaped transversely substantially similar to the shape of said rollers, and devices for adjusting the swingable shoe on its support relative to the 5 periphery of the adjacent roller.
3. In a machine of the class described, the combination of a pair of rollers, a shoe arranged at one side of said rollers and extending therefrom, said shoe being coöperable with said rollers to bend a section of metal on transverse lines, and means for 10 adjusting said shoe at an angle to a plane extending tangentially of the adjacent roller.
4. In a machine of the class described, the 15 combination of a pair of rollers, a shoe arranged at one side of said rollers and extending therefrom, said shoe being coöperable with said rollers to bend a section of metal on transverse lines, means for supporting said shoe to swing about the axis of one of said rollers, and means for adjusting said shoe at an angle to a plane extending tangentially of the adjacent roller.
5. In a machine of the class described, the 20 combination of a roller, a second roller, a shoe coöperable with said rollers to bend the section of metal on transverse lines, means for supporting said shoe in a plane substantially tangential to one of said rollers, and 25 means for adjusting said shoe perpendicularly to the tangential plane in which it is supported.
6. In a machine of the class described, the combination of a convex roller, a concave 30 roller, coöperable with said convex roller to bend a section of metal on longitudinal lines, a shoe shaped transversely substantially similar to the shape of said rollers, and coöperable therewith to bend the section 35 of metal on transverse lines, and means for supporting said shoe in a plane substantially tangential to one of said rollers, said supporting means being swingable about the 40 axis of the last mentioned roller, and said shoe being adjustable perpendicularly to the tangential plane in which it may be supported 45 by said supporting means.
7. In a machine of the class described, the combination of a convex roller, a concave 50 roller, coöperable with said convex roller to bend a section of metal on longitudinal lines, a shoe shaped transversely substantially similar to the shape of said rollers, and coöperable therewith to bend the section 55 of metal on transverse lines, and means for supporting said shoe in a plane substantially tangential to one of said rollers, said supporting means being swingable about the axis of the last mentioned roller, and said 60 shoe being adjustable at angles to the tangential plane in which it may be supported by said supporting means.
8. In a machine of the class described, the combination of a convex roller, a concave 65 roller, coöperable with said convex roller to bend a section of metal on longitudinal lines, a shoe shaped transversely substantially similar to the shape of said rollers, and coöperable therewith to bend the section of metal on transverse lines, and means for 70 supporting said shoe in a plane substantially tangential to one of said rollers, said supporting means being swingable about the axis of the last mentioned roller, and said shoe being adjustable toward and from said 75 rollers, and at an angle to the tangential plane in which it may be supported by said supporting means.
9. In a machine of the class described, the combination of a frame, a pair of shafts 80 mounted therein, one of said shafts being movable toward and from the other shaft in a plane cutting their axes, a pair of supports, swingably mounted on the stationary shaft, and eccentrics mounted in said 85 supports for moving the movable shaft toward and from said stationary shaft.
10. In a machine of the class described, the combination of a pair of rollers, a shoe arranged on one side of said rollers and coöperable therewith to bend a section of metal 90 on transverse lines, a separate shoe arranged on the opposite side of said rollers for guiding the metal section thereto, said shoes being shaped transversely substantially 95 similar to the shape of said rollers and disposed in a plane or planes extending tangentially to the periphery of one of them, means for supporting said shoes, the supporting means for said bending shoe being swingable about the axis of the last mentioned roller, means for adjusting said guiding shoe vertically, and means for adjusting 100 said bending shoe perpendicular to the tangential plane in which it may be supported 105 by said supporting means.
11. In a machine of the class described, the combination of a pair of rollers, a shoe arranged on one side of said rollers and coöperable therewith to bend a section of metal 110 on transverse lines, a separate shoe arranged on the opposite side of said rollers for guiding the metal section thereto, said shoes being shaped transversely substantially similar to the shape of said rollers and disposed 115 in a plane or planes extending tangentially to the periphery of one of them, means for supporting said shoes, the supporting means for said bending shoe being swingable about the axis of the last mentioned roller, means for 120 adjusting said guiding shoe vertically, and means for adjusting said bending shoe longitudinally of and perpendicular to the tangential plane in which it may be supported 125 by said supporting means.
12. In a machine of the class described, the combination of a pair of standards provided with guides, a pair of roller carrying

shafts one of which is slidably mounted in said guides, and means for raising and lowering said slidably mounted shaft, said means comprising a pair of arms swingable on the other shaft and eccentrics mounted in said arms and engaging said slidably mounted shaft.

In testimony whereof I affix my signature, in the presence of two witnesses.
